Attorney.

UNITED STATES PATENT OFFICE.

JESSIE C. BRADLEY, OF OAKLAND, CALIFORNIA.

AUXILIARY HEATING-PLATE.

1,391,166.

Specification of Letters Patent. Patented Sept. 20, 1921.

Application filed October 27, 1920. Serial No. 420,008.

To all whom it may concern:

Be it known that I, JESSIE C. BRADLEY, a citizen of the United States, residing at Oakland, in the county of Alameda and State of California, have invented certain new and useful Improvements in Auxiliary Heating-Plates, of which the following is a specification.

My invention is a warming device applicable to stoves for keeping the foods warm.

Referring to the annexed drawing in which my invention is illustrated, and which forms a part of this specification:

Figure 1 is a side elevation of one form of my warming plate applied to the under side of the top plate of a gas stove, said plate being shown in section.

Fig. 2 is a plan view of the warming plate shown in Fig. 1.

Fig. 3 is a plan view of another form of my warming plate.

Fig. 4 is a side view of the warming plate shown in Fig. 3.

Fig. 5 is a side view of another form of my warming plate applied to the top of the top plate of a gas stove, the top plate being shown in section.

Fig. 6 is a plan view of the plate shown in Fig. 5.

The form of my invention shown in Figs. 1, 2, 5 and 6 includes a ring 1, a plate 2 and a connecting member 3 which connects said ring and said plate. The connecting member 3 has a bend 4 in it which offsets the ring

1 above the plate 2, so that the device may be placed under the top plate 5 of a gas stove with the ring 1 resting against the under side of said top plate around its burner opening 6, and with the connecting member

2 extending under the depending edge flange 7 of said top plate and the plate 2 outside said flange. The device is detachably secured to the top plate 5 by a bolt 8, which extends through said top plate and

an aperture 9 in the connecting member 3; a nut 10 which screws on the lower end of said bolt against said connecting member,

and a butterfly nut 11 which screws on the upper end of said bolt against the top of said top plate and draws the ring 1 against 50 the under side of the top plate and the connecting member 3 against the lower edge of the edge flange 7. The stove burner 12 which is mounted under the burner opening 6 directs its flame through the ring 1 and 55 said opening.

The form of my invention shown in Figs. 3 and 4 includes a grid 15, a plate 16 and a connecting member 17 in which is a bend 18 which offsets the plate 16 above the grid 60 15. The grid 15 rests within the opening 6 of the stove top plate 5 upon lugs 19 projecting from the under side of the top plate under said opening and the plate 2 rests above the top plate by reason of the bend 18. 65

The ring 1 of the form of my invention shown in Figs. 5 and 6 rests upon the stove grid 20 which rests within the opening 6 on the lugs 19, and the plate 2 rests over the top plate 5. 70

Food in a receptacle is kept warm when the receptacle is placed on either of the plates 2 or 16.

Having described my invention, I claim:

1. A warming device including a ring 75 adapted to rest under the top plate of a stove around the burner opening, a plate resting outside the depending edge flange of said top plate, a connecting member connecting said ring and said plate, and means for 80 mounting the device under the top plate.

2. A warming device including a ring adapted to rest under the top plate of a stove around the burner opening, a plate resting outside the depending edge flange of 85 said top plate, a connecting member connecting said ring and said plate, a bolt extending through said connecting member and said top plate, and a nut screwing on the upper end of said bolt against the top 90 plate to hold the device in position under said top plate.

In testimony whereof I affix my signature.

JESSIE C. BRADLEY.
